MACHINE FOR TREATING METALLIC SHEETS

Custis S. Woolford, South Orange, N. J., assignor to American Can Company, New York, N. Y., a corporation of New Jersey

Application April 11, 1935, Serial No. 15,862

14 Claims. (Cl. 15—77)

The present invention relates to a machine for treating metallic sheets so that portions may be united with other portions of the same or with other sheets and has particular reference to devices for cleaning and abrading marginal surfaces of sheet material such as container body blanks, the edges of which are to be secured together as by soldering, welding, brazing or the like.

An object of the invention is the provision of a machine for abrading portions of metallic sheets such as container body blanks wherein marginal surfaces of the blank are mechanically cleaned and scoured to present a surface of virgin metal so that such surfaces may be effectively united in a subsequent operation.

Another object is the provision of such a sheet cleaning machine wherein the sheets are moved continuously along a path of travel passing through a plurality of cleaning stations having rotating cleaning elements which successively abrade the top and bottom marginal surfaces along opposing edges as the sheets pass by, after which the sheets are delivered into a magazine and automatically arranged in stack formation.

Still another object is the provision of a machine of the character described wherein the edges to be cleaned are moved vertically into engagement with the cleaning elements as the sheets pass through the stations, the forward movement of the sheet as it approaches a cleaning element results in actuation of detecting devices which delay the vertical movement of the edges until the forward corners of the sheet are well under the cleaning element so as to prevent mutilation of the same.

A further object is the provision in such a surface cleaning machine of control devices which govern the rotations of the cleaning elements so that their rotations are periodically reversed to prevent wearing away of the element in one direction, the reversal being effected automatically when a predetermined number of sheets have been cleaned.

Numerous other objects and advantages of the invention will be apparent as it is better understood from the following description, which, taken in connection with the accompanying drawings, discloses a preferred embodiment thereof.

Referring to the drawings:

Figure 1 is a side elevation of a machine in which the instant invention is embodied, parts being broken away;

Fig. 2 is a top plan view of the machine, with parts broken away;

Fig. 3 is an enlarged transverse section taken substantially along the vertical line 3—3 in Fig. 1, parts being broken away;

Fig. 4 is a fragmentary detail section of certain of the parts illustrated in Fig. 3 but showing these parts in a different position;

Fig. 5 is an enlarged fragmentary detailed plan view taken substantially along the horizontal line 10 5—5 in Fig. 3;

Fig. 6 is an enlarged transverse section taken substantially along the vertical line 6—6 in Fig. 1, and having parts broken away; and

Fig. 7 is a wiring diagram of the electric controls associated with the machine.

In the illustrated and preferred embodiment of the invention, sheets or blanks *a* are horizontally positioned, by any suitable means, on a conveyor which carries them through cleaning stations A and B. These stations have associated continuously rotating cleaning elements for scouring or abrading marginal surfaces of a blank along opposite sides and on top and bottom.

The blanks, in passing through the stations, engage trip levers which, when moved, release spring held instrumentalities which press the opposed margins of the blank into engagement with the cleaning elements. At the station A the marginal side edges of the blank are pressed up and its top marginal surfaces are cleaned. At the station B the sides of the blank are depressed and its bottom marginal surfaces are cleaned.

Thus both top and bottom marginal surfaces along the side edges of each blank are cleaned or abraded to expose the virgin metal. This cleaning action provides surfaces free from any foreign matter and these surfaces are then in proper condition for uniting by a subsequent soldering, welding, brazing or the like operation.

After passing the stations A, B the blanks are carried to the end of the conveyor and there transferred into an inclined chute. The blanks slide down the chute by gravity, passing over an air blast opening which at the proper time directs a jet of air against the bottom surface of the blank. This sets the blank up on its front edge and while still in this position it continues to slide down the chute until it comes to rest in stack formation at the bottom of the chute. The 50 shape and position of the chute permits easy removal therefrom of the cleaned sheets.

The sheets or blanks *a* (Figs. 1 and 2) are carried through the machine for the cleaning operation on a pair of spaced and parallel endless chain 55

conveyors 11. These conveyors are provided with spaced feed dogs 12 which engage behind the blanks and hold them in proper position while they are being carried forward. Other spaced 5 stop dogs 13 also provided on the conveyors are positioned in front of the blanks to prevent their longitudinal displacement during the cleaning operation.

The conveyors 11 extend the full length of the 10 machine and move between a pair of spaced, parallel side frames 15. These frames are tied together at each end by integral web sections 17, 19, which are formed into legs by which the entire 15 machine may be supported.

15 At the blank inserting or feed end of the machine (to the left as viewed in Fig. 1) the conveyor chains 11 take over spaced idler sprockets 21 which are pinned to a cross shaft 22 journaled in bearings 23 formed in the side 20 frames 15. At the opposite or discharge end of the machine the conveyor chains take over similarly spaced drive sprockets 25 which are mounted on a horizontal sprocket shaft 26 journaled in bearings 27 formed in the side frames 15.

25 In this manner the upper runs of the conveyor chains move horizontally and just below the top surface of the side frames. These side frames serve as guides for the blanks as the latter are carried along between them.

30 The sprocket shaft 26 is driven through a sprocket 28 (Fig. 2) which is mounted on an end of the sprocket shaft where it projects beyond one of the frames 15. This sprocket 28 is actuated by a chain 29 carried on a drive sprocket 32 35 which is mounted on an end of a driven shaft 33. Shaft 33 is journaled in suitable bearings formed in a bracket 35 which is bolted to the web member 19.

Shaft 33 also carries a bevel gear 36 (Fig. 1) 40 which meshes with a similar gear 37 mounted on one end of a longitudinal cam shaft 38. The cam shaft is carried in a bearing 41 formed in the web member 19 and in a bearing 42 formed in the opposite web member 17. A collar 43 45 pinned on the shaft adjacent the bearing 42 prevents longitudinal displacement thereof.

The cam shaft 38 is continuously rotated from a suitable source of power such as an electric motor 45. For this purpose the cam 50 shaft carries a spur gear 46 which meshes with a pinion 47 mounted on a short shaft 48 which is secured in a boss 49 formed on the web member 17. A collar 51 pinned to the opposite end of the shaft prevents displacement of the pinion.

55 The pinion 47 is formed as an integral part of a gear 52 which meshes with a main driving pinion 53 mounted on the motor shaft. Thus continuous rotation of the motor is transmitted through this gear train to the cam shaft which 60 in turn actuates the driven cross shaft 33 and its sprocket to drive the conveyors 11.

A blank *a* as it is being carried forward on the conveyor chains 11 first passes through the 65 cleaning station A. This station contains a set of four cleaning elements or brushes disposed in pairs on each side of the machine, each pair being located above or below the path of travel of the side marginal edges of the moving blank (Figs. 1, 2 and 3).

70 Each brush comprises a plurality of vertically disposed hardened steel wires 55 (see also Fig. 5) which at their upper ends are set in a ring 56. The ring in turn is loosely mounted on a cylindrical mandrel 57 the upper end of which is re-

duced in diameter and rotatably carried in a bearing 59.

Bearing 59 is formed on a bracket 61 which is bolted to the top of a table 62 which extends laterally from the side of the frame 15 and is formed integrally therewith. There are two of these brackets 61 at station A, one on each side of the machine and similarly there are two tables 62, one on each side.

The brush wires 55 are held compactly in 10 place around the mandrel 57 by an encircling tubular shell 64. The upper end of the shell 15 engages over an enlarged head 65 of the mandrel and is drawn tightly against a shoulder 66 by a collar 67, which fits over the top of the shoulder and threadedly engages the top of the shell.

The bottom cleaning end of each wire brush 20 55 extends down below the bottom edge of the shell 64 and the mandrel 57 and parts carried thereby may be adjusted up or down to properly 25 position the brush to engage the surface of the blank to be cleaned. For this purpose the brush ring 56 is connected by a horizontal pin 71 to a central vertical rod 72 disposed in a vertical 30 bore 73 formed in the mandrel 57. The pin 71 is carried in the lower end of the rod and extends transversely on both sides passing through an elongated slot 74 formed in the mandrel. The ends of the pin are secured in suitable bores 35 formed in the ring 56.

The upper end of the rod 72 is reduced in diameter and extends through a tubular bushing 76 which threadedly engages within the upper 40 part of the mandrel bore 73. A collar 77 pinned to the top end of the rod, holds the latter in the bushing. Manual turning of the bushing within its threaded seat adjusts the brush into the desired vertical position. This position is then maintained by a lock nut 78 which threadedly 45 engages the bushing and which is screwed down against the top of the mandrel.

Each of the pair of brushes on a side is rapidly 50 rotated but in opposite directions and each front or rear brush rotates in a different direction to 45 the corresponding brush on the opposite side of the machine. This is effected by a gear train on each side of station A which connects the pair of brushes on that side with an independent 55 source of power, preferably an electric motor.

For this purpose the reduced upper end of each brush mandrel 57 extends above its bearing 59 and is keyed to a gear 81 (Figs. 2 and 3). These gears mesh with a pair of intermediate 60 idler gears 82 mounted on short shouldered studs 83 which are riveted in place in bosses 80 formed on the bracket 61.

One of the idler gears meshes with a driving gear 84 mounted on the end of a vertical shaft 85 journaled in a bearing 86 formed on the 65 bracket 61. Shaft 85 may be the motor shaft of a continuously rotating electric motor 87 which is bolted to the table 62 adjacent the bracket 61. There are therefore two of these 70 motors at station A one for each side of the machine.

As a blank *a* passes through the station A its side edges are lifted into engagement with the 75 rotating brushes. During this passage the blank is held against vertical displacement along its center by a pressure bar 91 which extends across and through both stations A and B (Figs. 1, 2 and 3). The bar is thus disposed longitudinally of the machine and is hung in place and supported at its ends on transverse plates 92 which are in 75

turn secured to the top edges of the side frames 15.

The moving blank successively engages the first and second pair of brushes 55 at station A thus completing the cleaning operation on its upper surface in two stages. At each of these stages of cleaning the blank is lifted by instrumentalities which will now be described, the construction and operation for each brush being identical and hence a description of only one of these sets being sufficient.

A pair of bell cranks 93 (Figs. 1, 2 and 3) are disposed on each side of the machine one under each of the brushes 55. Each crank is mounted 15 on a short shaft 94 which is carried in bearings 95 formed in a bracket 96 which may be an integral part of the side frame 15. Each bell crank is provided with a substantially horizontal leg 98 which extends under the side edge of the blank 20 when the latter is passing through the station terminating in an elongated pad 99. It is this pad 99 that engages under the edge of the blank and lifts it into contact with the brush.

Each bell crank is also provided with a substantially vertical, depending leg 101. The lower end of this leg is engaged by one end of a coiled spring 102 and the other end of the spring is secured into an eye bolt 103 which in turn is threadedly seated in the side of the frame 15. It is these 30 springs which under certain conditions pivot the cranks on their shafts and cause the pads 99 to lift the blank into cleaning engagement with the brushes.

The bell cranks 93 are held depressed until a blank *a* is presented for cleaning, the release of the cranks being effected during the forward movement of the blank by the latter releasing certain holding elements. These elements comprise latch arms 105 and one end of each arm 40 engages against and holds back its associated bell crank leg 101 when the holding elements retain the bell cranks depressed (Fig. 3).

Each arm 105 is held in leg engaging position by a spring 107 (Figs. 1 and 2). One end of the 45 spring engages a depending lug 108 which is formed as an integral part of the arm while the other end is hooked in an eye 109 secured in the side of the adjacent frame 15.

Each latch arm 105 is mounted at the end of one or the other of a pair of horizontal cross shafts 111 carried in bearings 112 formed in the side frames 15. Each shaft is disposed under the upper run of the conveyor chains 11 and carries a trip finger 113 which extends forward and longitudinally of the pressure bar 91. The free end of the finger when not engaged by a blank extends up into the path of travel of the blank and into a clearance slot 114 formed in the pressure bar.

Thus a blank *a* moving toward the brushes at station A engages first one and then the other of the trip fingers and rocks the associated shaft and the two latch arms thereon. This is done against the resistance of the spring 107. The forward ends of the arms are thus lowered and move adjacent a notch or set back 110 (Fig. 3) formed in the leg 101 of each bell crank 93 and this unlatches or releases the associated bell cranks.

The lifting of the blank, however, is delayed until its front edge is well under the brush. This 70 is done to prevent the forward corners of the blank from being mutilated or damaged by the brushes. When released from the holding latch, a crank 93 is held back by a cam actuated auxiliary bell crank 115 (Fig. 3).

75 The auxiliary bell crank is mounted on a pin

116 carried in lugs 117 formed on the side of the frame 15. The upper end of a substantially vertical leg 118 of the crank is in the path of a setscrew 119 carried in the lower end of the bell crank leg 101 when the latch arm 105 is moved opposite the notch 110. This setscrew therefore engages the leg 118 and the bell crank 93 is prevented from further movement.

Another leg 121 of the auxiliary bell crank extends through an opening 122 formed in the side 10 of the frame 15 and carries a cam roller 123. Roller 123 operates with an edge cam 124 which is mounted on the cam shaft 38 and in the position shown in Fig. 3 the cam is on its high point and holding the leg 118 in its outer position. Engagement between roller and cam of each auxiliary bell crank 115 is maintained by a spring 125 having one end hooked into an aperture 126 formed in the auxiliary crank leg 118 and the other end in an eye bolt 127 secured in the side of 20 the frame 15.

When the front edge of the blank is fully under the brushes the cams 124 move to low point position and thereupon the springs 125 pull the legs 118 inwardly and the bell cranks 115 rock 25 on their shafts 116 the upper ends of the legs 118 moving out of the way of the setscrews 119. This permits the springs 102 to pivot the bell cranks 93 on their pivot shafts and to lift the blank into engagement with the brushes as illustrated in Fig. 4.

The whirling scraping action of the brushes together with the forward travel of the blank abrades its upper marginal surfaces as illustrated in Fig. 5. The high speed of rotation of the 35 brushes and the constant changing of the engaged surfaces as brought about by the advancement of the blank is very effective. In addition the two stage or double cleaning action insures full abrasion of the surface down to the virgin 40 metal.

Constant rotation of the brushes in one direction while cleaning the blanks gradually wears the ends of the wires flat or at a slight angle and to lengthen the life of their effective cleaning 45 action provision is made for automatically reversing the direction of rotation of all the brushes simultaneously after a predetermined number of blanks have been cleaned. This action causes the wires of the brush to slightly flex in the opposite direction and to present the sharp angular portion of the face of the wire to the blank surface instead of the flat worn edge. This in its effect is equivalent to renewing the abrading action of the wires.

The electric motors which drive the brushes are of the reversible type and are controlled by reversing devices. These devices are electrically associated with the power circuits which are schematically illustrated in the wiring diagram 60 in Fig. 7 and will be fully explained in connection with a subsequent detailed description of that figure.

After the cleaning operation at station A, continued forward movement of the conveyors 11 65 carries the blank through station B. While passing through this latter station its lower marginal surfaces are subjected to the same kind of a cleaning operation. Station B is also provided with a set of four cylindrical wire brushes 70 designated by the numeral 141 (Figs. 2 and 6) which are similar in construction to the brushes 55 and which are also arranged in pairs. The brushes 141 are located below the upper run of the conveyor and are in an inverted position 75

being disposed in openings 142 formed in the side frames 15.

Each brush is supported on the lower end of a mandrel 143 which extends up above the brush in a reduced diameter which is journaled in a stationary bearing 144. Bearing 144 is formed in a bracket 145 which is bolted to the top of a table 146 extending laterally from the outer side of the frame 15. There are two of these brackets 145 and two tables 146, one for each side of the machine and supporting the brushes and associated parts located on that side.

The wires of each brush are held in compact cylindrical form by an encircling tubular shell 147 corresponding to the shell 64 of the brushes 55. The lower end of the shell is mounted on a lower shouldered part 148 of the mandrel 143 and is locked in position by a nut 149 threadedly engaged therewith. The brush is connected to a 20 centrally disposed vertical rod 152 by a horizontal cross pin 153 which passes through the lower end of the rod and through a vertical slot 154 formed in the mandrel. The ends of the pin are engaged in a ring 155 this being a ring in 25 which the brush wires are embedded.

The rod 152 is adjustably carried in a central bore 157 formed in the mandrel and at its upper end the rod is shouldered similar to the rod 72. This shouldered end of rod 152 extends beyond 30 the mandrel 143 and through an adjusting sleeve 158 which is threadedly engaged in the upper end of the bore 157. A collar 159 secured to the rod holds the sleeve in position. By turning the sleeve, the rod and hence the brush may be adjusted vertically. When adjusted the parts are held by a lock nut 161 which threadedly engages the sleeve and clamps on the upper end of the mandrel.

Like the brushes 55, the brushes 141 are continuously rotated at high speed. This is effected by driving units identical in construction with the devices used in connection with the brushes at station A. Each mandrel 143 carries at its upper end a gear 165. The two gears on each side of the machine mesh with a pair of intermeshing gears 166 mounted on shouldered studs 167 secured in bosses 168 formed on the brackets 145.

One of the gears 166, on each side of the machine, meshes with a driving gear 169 carried on one end of a shaft 171 journaled in a bearing 172 formed in the bracket 145. The shaft 171 is the main drive shaft of an electric motor 173 which is mounted on the table 146 adjacent the bracket.

There are two of these motors, one for each side of the machine, and there is in this manner an independent drive for each set of brushes on a side. Like the motors associated with the station A, the motors 173 are of the reversible type 60 and are controlled electrically by the same devices and for the same purpose. This will be hereinafter explained in connection with Fig. 7.

In station B the lower side marginal surfaces of the moving blank *a* are depressed into engagement with the rotating brushes 141 for the cleaning operation. This cleaning is effected in two stages as at the station A, each stage utilizing a separate transverse pair of brushes. The depressing instrumentalities for each stage are in 70 duplicate and are identical in construction and operation hence only one of the sets will be described.

Depression of the side edges of the blank is effected by bell cranks 175 (Figs. 1, 2 and 6) there 75 being two of these on each side of the machine

above the brushes 141. The bell cranks are mounted on short shafts 176 carried in bearings 177 formed in brackets 178 which may be an integral part of the frames 15. Each crank has a substantially horizontal leg 181 which terminates at its outer end in an elongated pad 182 which engages the side edge of the blank when it is pressed into engagement with the brush.

Actuation of each crank so that its pad engages the blank is effected by a spring 183. One 10 end of the spring is hooked over a depending leg 184 of the crank and the other end is hooked over a lug 185 depending from the bottom of the table 146. The cranks 175 are held in raised position until a blank is passed into the station 15 for cleaning. This is effected by latch arms 187 of holding elements one end of each latch arm providing an interference for its associated crank leg 184.

The latch arm is held in this stop position by a 20 coil spring 189 having one end engaged in a lug 191 (Fig. 1) formed as an integral part of the arm. The other end of the spring is hooked over a pin 192 secured in the frames 15.

The latch arms 187 are mounted on the ends of 25 one of two horizontal cross-shafts 195 carried in bearings 196 formed in the side frames 15. Intermediate the bearings and disposed directly under the pressure bar 91, each shaft carries a trip finger 197 (Fig. 6) which normally projects 30 up and into a slot 198 cut through the bar. As at the station A there is one of these fingers for each stage of cleaning.

These fingers are successively engaged by the forward edge of the advancing blank coming into 35 the station and when so tripped the latch arms are shifted to a position alongside of a notched or recessed part 199 of the leg 184. The bell cranks 175 are thus freed from the action of the latch arms or holding elements. Movement of the associated bell crank, however, is delayed until the forward edge of the blank is well over the top of the brush at that position. This is to prevent the forward corners of the blank being mutilated or 40 damaged by the brushes.

This delayed action is brought about by an actuated auxiliary bell cranks 201 (Fig. 6) mounted on short shafts 202 which are carried in lugs 203 formed in the frames 15. One leg of each auxiliary bell crank is indicated by the reference character 205 and this leg carries a setscrew 206 at its upper end. The other leg, indicated by the reference character 207, extends through an opening 208 formed in the frame 15 and carries at its end a cam roller 209.

Cam roller 209 engages with an edge cam 211 carried on the cam shaft 38 the roller being kept in engagement with the cam by a coiled compression spring 213. This spring is seated at 214 in the frame 15 and its outer end engages against 60 a pad 215 formed on the auxiliary bell crank leg 205.

The cam is rotated in time with the travel of the blank on the conveyor 11 and thus when the front edge of a blank is properly located over the 65 top of a set of brushes, either at the first or second stage, the cams 211 move the auxiliary cranks 201 and carry the setscrews back and out of holding position. This fully releases the bell cranks 175 which are thereupon moved by the 70 springs 183 and this brings the bell crank pads 182 into blank engaging position and depresses the blank into engagement with the brushes.

This action together with the forward movement of the blanks and the rapid whirling action 75

of the brushes cleans the bottom marginal surfaces of the blank in the same way as the upper marginal edges were cleaned at the station A. After passing through both of the stages of cleaning at the station B, the blank is in condition for a subsequent soldering, welding or similar operation which, however, forms no part of the present invention.

At the discharge end of the conveyor 11 the blanks are piled up in stack form within a magazine. As the conveyor chains take over the sprockets 25 a freshly cleaned blank carried thereon rides off of the chains and falls into an inclined chute 215 (Figs. 1 and 2) which constitutes the magazine. This chute is mounted on an inclined base 216 formed on the bracket 35.

As a blank slides down into the chute it is set up on edge by a blast of air directed against its under or sliding surface. This is effected by actuation of an ordinary push valve 218 of suitable construction which is connected in a pipeline 219 having one end threadedly engaged in a bore 221 extending through a boss 222 formed in the bottom of the base 216. The bore 221 aligns with an aperture 223 cut through the bottom of the chute. The other end of the pipe is secured in a clamp 225 formed in the bracket and may be connected to one end of a flexible hose 226 leading from a suitable source of compressed air.

The stem of the valve 218 is provided with a spring held button 228 which is struck by the high part of an edge cam 229 mounted on the constantly rotating conveyor drive shaft 33. The cam periodically depresses the valve stem and momentarily opens the valve and this is done in time with the travel of the conveyor and hence with the discharge of blanks into the chute.

As a blank slides down the chute the valve is opened as it moves past the aperture 223 and a blast of air is directed against the blank from the bottom side and adjacent its upper edge. This causes the blank to be set up on edge as shown in Fig. 1. The momentum of the sliding blank is sufficient to carry it the remainder of the way down the chute in this set up position or until it strikes the blanks already stacked and held against holding flanges 231 formed at the bottom end of the chute.

The electric motors associated with the machine are preferably of the three phase type and are connected by a three phase system of wiring to a suitable source of electric energy such as a generator 301, as schematically shown in the wiring diagram in Fig. 7. The generator is provided with service wires 302, 303, 304 which transmit the current through a three phase service switch 305 to lead wires 311, 312, 313. One end of these latter wires are connected to the motor 45 which drives the moving parts of the machine proper.

The reversible motors 81, 173 which actuate the blank cleaning brushes 55, 141 are connected into lead wires 315, 316, 317 which in turn are connected to one set of terminals of a pair of three phase, solenoid actuated, reversing switches 318, 319. The opposite set of terminals of these switches are connected by wires 321, 322, 323 to the wires 311, 312, 313 by means of which electric energy is supplied to the motors. It is the alternate closing of the switches 318 or 319 which reverses the direction of rotation of the motor shafts to change the direction of rotation of the brushes as hereinbefore mentioned.

The alternate closing of the switches 318, 319 is effected by alternate energization of solenoids 325, 326 which are respectively associated with

the switches. One terminal of the solenoid 325 is connected by a wire 327 to the wire 313. The other terminal is connected by a wire 328 to one side of a two way switch 329 having a movable element 330. The switch 329 is located in a switch box 331 which is conveniently secured to the side of the frame 15 (see also Figs. 1 and 2). The movable element is connected by a wire 332 to the wire 311.

One side of the solenoid 326, which is associated with the switch 319, is connected by a wire 333 to the wire 313. The other side of the solenoid is connected by a wire 334 to the opposite side of the two way switch 329. Thus when the movable element 330 of the two way switch is in contact with the terminal end of the wire 328 the solenoid 325 is energized and the switch 318 is thereby closed sending electric energy through the motors in one direction. Similarly when the element 330 is moved into contact with the terminal end of the wire 334 the solenoid 325 is de-energized and the solenoid 326 is energized thus opening the switch 318 and closing the switch 319 so as to send electric energy through the motors in a reverse direction thus reversing their rotation.

The switch element 330 is moved at intervals when a predetermined number of blanks have been cleaned. This is effected by any suitable means mechanically actuated in time with the passage of blanks on the conveyor chains. A preferred form of device comprises a ratchet arm counter 340 of any suitable construction which may be housed in the switch box 331. An arm 341 extending into engagement with the leg 101 of one of the bell cranks 93 may constitute the ratchet arm to actuate the counter.

Movement of the crank leg when lifting a blank into engagement with the brushes 55 will thus function as the actuator for moving the counter arm 341. The counter may be set so as to shift the movable switch element 330 after any predetermined number of blanks have been cleaned and thus reverse the motors. As there are any number of suitable commercial types of counters which can be used successfully, further and more detailed description is thought unnecessary.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A machine for cleaning metallic sheets comprising in combination, means for supporting sheets to be cleaned and for conveying them through the machine, abrading means associated with said supporting means, and instrumentalities for pressing the sheets against said abrading means to clean a surface thereof, said abrading means acting on both ends of the sheet for the width of the latter.

2. A machine for cleaning metallic sheets comprising in combination, means for supporting sheets to be cleaned and for continuously conveying them through the machine, abrading means associated with said supporting means, and instrumentalities for pressing a marginal edge of a said sheet against said abrading means while being conveyed to clean a surface thereof, said instrumentalities maintaining both ends of

- said sheet in contact with said abrading means for the full width of the sheet and for a limited length thereof.
3. A machine for abrading metallic sheets comprising in combination, rotating hard and flexible filaments for abrading a sheet surface, instrumentalities for pressing the sheets against the ends of said filaments, and control devices actuated by a sheet when in proper position relative to said abrading elements for rendering said instrumentalities effective.
4. A machine for cleaning metallic sheets comprising in combination, means for supporting the sheets to be cleaned, and a rotating hollow wire brush element associated with said supporting means and rotating on an axis which is substantially perpendicular to the surface of said sheets for abrading a surface thereof, said hollow brush element having means disposed on opposite sides of the brush filaments for holding the same compactly together, and means for pressing the end portion of the sheet against the ends of the brush wires.
5. A machine for cleaning metallic sheets comprising in combination, an abrading element for cleaning a surface of said sheets, said abrading element consisting of metal filaments disposed in parallel relation to one another and having means for holding the filaments thereof compactly together, conveyor means for moving said sheets and for presenting them to said abrading element, instrumentalities for moving a surface of said sheets into engagement with the ends of the filaments of said abrading element, means for detecting the presence of a sheet when it is presented to said abrading element and for rendering operable said instrumentalities, and means for rotating the abrading element on an axis perpendicular to the sheet.
6. A machine for cleaning metallic sheets comprising in combination, an abrading element for cleaning a surface of said sheets, said abrading element consisting of metal filaments disposed in parallel relation to one another and having means for holding the filaments thereof compactly together, continuously operating conveyor means for moving said sheets past said abrading element, instrumentalities rendered operable by a said sheet during its movement by said conveyor for moving a surface of said sheet into engagement with the ends of the filaments of said abrading element, means for causing actuation of said instrumentalities in timed relation with the movement of said conveyor, and means for rotating the abrading element on an axis perpendicular to the sheet.
7. A machine for abrading metallic sheets comprising in combination a rotary abrading element consisting of hard metallic filaments and means for holding the filaments compactly together, conveyor means for moving said sheets past said abrading element, devices for continuously rotating said abrading element, and means for reversing the direction of rotation of said abrading element, to compensate for the wear of the same in response to the passage by said conveyor of a predetermined number of sheets past said abrading element.
8. A machine for abrading metallic sheets, comprising in combination a plurality of abrading elements for cleaning surfaces of said sheets, said abrading elements consisting of hard metallic filaments and means for holding said filaments compactly together, conveyor means for moving said sheets past said abrading elements past said abrading elements for continuously rotating said abrading elements, devices for reversing the direction of rotation of said abrading elements, and means for compensating for the wear of the same in response to the passage by said conveyor of a predetermined number of sheets past said abrading elements.
9. A machine for cleaning metallic sheets comprising in combination, rotating abrading elements comprising a plurality of wires and means for holding them compactly together with said wires arranged parallel to their axis of rotation for cleaning a sheet surface, means for conveying the sheets to pass their marginal edges adjacent said abrading elements, instrumentalities for pressing said marginal edges of the sheets against the ends of the wires of said abrading elements, and control devices for said instrumentalities for preventing engagement between a sheet and said abrading elements while the forward part of a said marginal edge is approaching said elements.
10. A machine for cleaning metallic sheets comprising in combination, conveyor means for moving sheets along a desired path of travel, abrading elements disposed on opposite sides of said path of travel and on the same side of a said sheet, each abrading element consisting of a plurality of wires and means for holding the same compactly together and in parallel relation, and instrumentalities acting in opposite directions for pressing said sheets toward and into engagement with the ends of the wires of said abrading elements for cleaning opposite surfaces of said sheets.
11. A machine for cleaning metallic sheets comprising in combination, abrading elements for cleaning a surface of said sheets, each abrading element consisting of a plurality of wires and means for holding the same compactly together and with the wire ends facing in the same direction, conveyor means for moving said sheets past said abrading elements, instrumentalities for moving a surface of said sheets into engagement with the ends of the wires of said abrading elements, a latch member operable by said sheets for unlatching said instrumentalities, and holding means operable in time with the movement of said conveyor for delaying movement of said instrumentalities until after the front edge of said sheet is moved into a definite relation to said abrading elements.
12. In a machine for cleaning metallic sheets, the combination of a plurality of abrading elements disposed above and below a path of travel of said sheets and opposite to limited marginal portions only of said sheets, a magazine for receiving sheets in stack formation, a directing wall leading into said magazine and over which said sheets pass upon entering, conveyor means for moving said sheets along said path of travel and for placing them on said magazine directing wall, and air blast means in said magazine actuated in time with the movement of said sheets and directed through an opening in said wall for setting up said sheets on edge to arrange them in stack formation with the marginal abraded portions of said sheets in alignment with each other.
13. In a machine for cleaning metallic sheets, the combination of a plurality of abrading elements disposed above and below a path of travel

of said sheets and opposite to limited marginal portions only of said sheets, a magazine for receiving sheets in stack formation, a directing wall leading into said magazine and over which said sheets pass upon entering the magazine, conveyor means for moving said sheets along said path of travel and between said abrading elements and for placing them on said magazine directing wall, air blast means in said magazine and directed through an opening in said wall for setting up said sheets on edge to arrange them in stack formation with the marginal abraded portions of said sheets in alignment with each other, and devices for actuating said air

15

blast means in time with the movement of said sheets into said magazine.

14. A machine for cleaning metallic sheets comprising in combination a plurality of abrading elements disposed above and below a path of travel of said sheets and opposite to limited marginal portions only of said sheets, conveyor means for moving said sheets along said path of travel and between said abrading elements, and movable means associated with said abrading elements for bringing opposite marginal portions only of said sheets into engagement with said abrading elements for cleaning opposite surfaces of said sheets.

CUSTIS S. WOOLFORD. 15
